UNITED STATES PATENT OFFICE.

JAMES H. MITCHELL, OF SAN FRANCISCO, CALIFORNIA.

IMPROVEMENT IN LAUNDRY-STOVES.

Specification forming part of Letters Patent No. 142,259, dated August 26, 1873; application filed February 24, 1873.

To all whom it may concern:

Be it known that I, JAMES H. MITCHELL, of San Francisco city and county, State of California, have invented an Improved Laundry-Stove; and I do hereby declare the following description and accompanying drawings are sufficient to enable any person skilled in the art or science to which it most nearly appertains to make and use my said invention or improvement without further invention or experiment.

My invention relates to that class of stoves which are used for laundry purposes, and also by candy manufacturers for boiling sugar, and for like purposes. The object of my improvement is to concentrate the heat from the fire-place against the top of the stove, so that the greatest possible benefit can be derived from it before allowing it to escape up the stove-pipe.

In order to more fully illustrate and explain my invention, reference is had to the accompanying drawing forming a part of this specification, and which is a perspective view of my stove with the top removed, but its proper position indicated by dotted lines, being partially broken away.

A represents a stove of the class above named. The fire-place inside of this stove is constructed of soap-stone, or other fire-resisting material, and is made in the form of an open-topped box, B, which is smaller than the outside iron shell of the stove, so that a space, e, will be left entirely around it between its outside and the outer shell of the stove. The grate C is placed in the bottom of the box B, in the usual manner. The sides of the box B slope outwardly toward the top, and extend upward to within a short distance of the top

of the stove-shell A, inside, when the back and rear half of the two sides are extended outward at a greater angle, as shown at *ff*, so as to meet the upper edges of the sides of the shell A, thus leaving an opening, *i*, on each side at the front of the stove, through which the products of combustion will pass on their way to the draft-pipe, which communicates with the space between the box B and stove-shell at the back of the stove. (Not shown in the drawing, but its position indicated by dotted lines.)

By constructing the stove with only the two side openings at the upper front of the stove, through which the products of combustion must pass, all of the heat will necessarily strike the top of the stove before passing into the space or jacket between the box and shell, thus obtaining the greatest possible benefit from the heat.

The bent tube *bb* is the ordinary water-pipe usually placed in stoves of different constructions.

Having thus described my invention, what I claim, and desire to secure by Letters Patent, is—

The stove A, having the sloping fire-box B smaller than the stove-shell, and provided with the flaring back and sides *ff*, so as to provide a jacket or space, *e*, between the two, when the only communication with said jacket or space is through side openings *ii*, substantially as and for the purpose above described.

In witness whereof I hereunto set my hand and seal.

JAMES HARVAY MITCHELL. [L. S.]
